(57) **CLAIM**

The ornamental design for a remote control, as shown and described.

DESCRIPTION

FIG. 1 is a front, bottom and right side perspective view of a remote control showing our new design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a rear, top and left side perspective view thereof; and,

FIG. 9 is a rear, top and left side perspective view thereof. The broken lines in the drawings showing portions of the remote control are included for the purpose of illustrating environmental structure and form no part of the claimed design.
